VENETIAN BLIND OPERATING FIXTURE

George D. Dodge, Evanston, Ill.

Application September 24, 1934, Serial No. 745,219

12 Claims. (Cl. 156—17)

This invention relates to a fixture for Venetian blinds, and particularly to sheave or roller mechanism and cord holding mechanism.

The primary object of the invention is to provide a fixture, having a plurality of sheaves, hereinafter termed "rollers", which are constructed and arranged to permit the operating cord of a Venetian blind to be operated from the front of the blind.

Another object of the invention is to provide a front operating cord holder for Venetian blinds, which comprises a unitary structure having rollers of different diameters, over which the operating cords pass, and which is provided with spaced rollers through which the cords pass, to impinge the cords and prevent downward movement of the Venetian blind due to its weight.

A further object of the invention is to provide a simple, compact, unitary structure adapted to be fastened to the top bar of a Venetian blind, and which is provided with rollers spaced at right angles to their axes, so that the cord may be positioned around one set of rollers and pass over another set of rollers to permit front operation of the Venetian blind, which fixture is also provided with spaced legs, having a pair of rollers arranged therebetween through which the cord is adapted to operate, the cord being impinged between the rollers when pull on the cord is released.

Numerous other objects and advantages will be apparent throughout the progress of the following specification.

The accompanying drawing illustrates a selected embodiment of the invention, and the views therein are as follows:

Fig. 1 is a detail elevation of a Venetian blind and embodying the invention.

Fig. 2 is a detail sectional view on the line 2—2 of Fig. 1.

Fig. 3 is a detail sectional view on the line 3—3 of Fig. 1.

Fig. 4 is a detail perspective view of the improved fixture, showing the cord holder in operative relationship therewith.

Fig. 5 is a detail sectional view on the line 5—5 of Fig. 2.

The Venetian blind herein shown, for the purpose of illustration, comprises an upper supporting member or top bar 6 which is fastened by means of bracket 7 to a window frame 8. A bracket 9 is operatively fastened to the top bar 6 and supports a tilting bar 10. Rollers 11 and 12 are revolvably mounted in the top bar 6, and an operating cord 13 passes over these rollers and

through aligned openings in the slats 14. Tapes 15 are fastened to the tilting bar 10 and to the Venetian blind bottom bar (not shown) to support the slats and to hold them in spaced relationship. The top bar 6 and the tilting bar 10, the manner in which the Venetian blind is operated, its mode of fastening, and the construction of the blind, are well known in this art, and therefore further description thereof need not be made.

A supporting fixture 16 is provided with a horizontal ledge or supporting portion 17 (Fig. 4) which is adapted to be fastened by suitable fastening means 18 to the top bar 6. The fixture 16 also comprises a vertically, downwardly extending, U-shaped or channel-shaped portion 19, comprising downwardly extending, oppositely disposed side legs 20 and 21 which are integrally connected by a rear portion 22. A pivot pin or axle 23 passes through the spaced legs 20 and 21 and supports a roller 24 and a smaller roller 25. These rollers are at right angles to operating rollers 26 and 27 which are mounted on a pivot pin between the ledge 17 and an integral ear 28 bent from a part of the ledge. The roller 26 is larger in diameter than the roller 27, the rollers 26 and 27 being substantially the same size as the rollers 24 and 25 respectively. The rollers 26 and 27 are also substantially the same size as the rollers 11 and 12, respectively. In other words, the rollers 11, 27 and 25, respectively, are smaller in diameter than the rollers 12, 26 and 24.

The operating cord 13 is a double cord, comprising an upper cord 29 and a lower cord 30. The cord 13, including both parts 29 and 30 thereof, passes over the rollers 11 and 12, the upper cord 29 passing over the large roller 12 and the lower cord 30 passing over the small roller 11. The upper cord 29 also passes over large roller 26, and then making a right-angle turn, passes over large roller 24. The lower cord 30 passes over the smaller roller 11 and the smaller roller 27 and then makes a right-angle turn, passing over smaller roller 25.

In the conventional form of Venetian blinds, a single roller of substantially a width equal to a pair of the present rollers is employed, the cord operating over this wider roller.

The double cord, when operating over the single or wide pulleys or rollers, has a tendency to twist and also to become dislodged from the roller and become impinged between the side of the roller and the edge surrounding the recess into which the roller is mounted. The use of the

double rollers of different diameters tends to hold the cords in their proper position, prevents twisting of the cords, and causes the blind to operate more easily.

5 A pin 31 passes through the spaced legs 20 and 21, and a roller 32 is arranged between the legs and is revolvably mounted on its pivot pin or axis 31. Rearwardly of the axis or pin 31 there is a second pin 33 which is mounted in opposite disposed slots 34 formed in the legs 20 and 21. A second roller 35 (Fig. 5) is revolvably mounted on the pin or axis 33. The second roller 35, therefore, has revoluble movement on its pin or axis 33, and inasmuch as the pin or axis 33 is slidably mounted in opposed slots 34, the second roller 35 may be said to have vertical slidable movement as well as rotative movement in respect to the legs 20 and 21.

10 The rollers 32 and 35 are substantially hexagonal in longitudinal cross-section, each being in the form of two frusto-cones or pyramids with their bases fixed together to provide a central portion 36 which is greater in diameter than the ends of the rollers. In other words, the rollers 25 32 and 35 have their greatest diameter at the center or crest 36 and taper off toward their ends 37. From the ends 37 of these rollers toward their center or crest 36, there are provided a plurality of facets which merge as at 38 (Fig. 5), 20 there being relatively diamond-shaped facets 39 between the contacting edges of the facets 38. Broadly, therefore, the rollers 32 and 35 may be said to be egg-shaped, having facets arranged about their peripheral surfaces. These rollers 35 are so constructed as to provide for instantaneous and positive gripping action on the cord the precise moment the cord is released from the operator's hand. This positive action is accomplished by the two rollers 32 and 35, the roller 32 being 40 fixed and in constant position, while the roller 35 is free to work upwardly and downwardly on its floating axis 33. The particular shape of the rollers 32 and 35 causes this gripping action. The consecutive flat surfaces or facets around the 45 entire periphery of each of the rollers is the nucleus of the positive gripping action, and the floating action of one of the rollers is the cause of the instantaneous feature. In practice, it has also been found that rollers constructed in accordance with rollers 32 and 35 cause no appreciable wear on the Venetian blind operating cord.

50 In applicant's co-pending application, Serial No. 745,220, filed September 24, 1934, another form of device embodying rollers similar to the 55 herein rollers 32 and 35 is disclosed and claimed.

The invention provides a compact, unitary structure adapted to be fastened to the top bar of a Venetian blind for causing positive and easy operation of the Venetian blind and permitting floating operation of the blind.

60 The rollers 11 and 12 mounted in the top bar, and the rollers 24, 25, 26 and 27 mounted in the fixture, tend to keep the cords in proper spaced relationship and prevent twisting thereof. The 65 cord-gripping rollers 32 and 35 provide a truly automatic device, in that as soon as the operator lets go of the hoist cord, the blind will automatically stop at the precise moment. There is no need of holding the cord or positioning it in any manner to cause the stop rollers to function. The high sensitiveness of the stop rollers does the work automatically. A slight tension must be kept on the hoist cord when the blind is to be lowered, as otherwise the sensitiveness of the 70 floating roller 35 will stop the action which, as

outlined above, it is its duty to do. Therefore, when the blind is only partly lowered, the cord will be gripped, but when it is desired to operate the blind, the cord is released when a slight tension is exerted thereon. During the lowering 5 operation of the blind, it is preferable that the cord be held out a slight distance so as to prevent contacting engagement of the cord with the rear or floating roller 35. When the cord is so held, the gripping action will cease and the roller 35 will drop to the bottom of its guide-slot 34. When the blind is raised by pulling on the cord, the roller 35 will stay in its lowered position. However, as soon as the cord is released, the reverse action or movement of the cord, then being 10 in engagement with the roller 35, will pull the roller 35 upwardly so that the cord will be impinged between the roller 35 and the roller 32. As soon as the cord is released, the movement thereof will cause the lower sliding roller to move 15 upward in its guide-slot 34, at which time it will be in gripping relationship in respect to the fixed roller 32. By making the rollers 32 and 35 relatively egg-shaped, that is, by having the rollers higher in the center and tapering off toward their ends, each part 29 and 30 of the cord 13 will be 20 properly divided and thereby avoid the trouble caused by the tendency of the cords to twist.

25 The invention also provides a Venetian blind fixture having a two-fold purpose. The first purpose is the provision of the rollers or sheaves of different diameters, whereby the cords will be divided and operate about their respective aligned rollers. This arrangement prevents the old troublesome twisting action of the cords. Another 30 important feature is that the double rollers or sheaves help to eliminate a considerable portion of the friction usually encountered in front operating blinds by preventing the cords from 35 twisting and by providing a single, separate roller or sheave for each part of the double cord. The combination of the automatic stop with the double roller or sheave type of front fixture is also of great aid and importance in preventing 40 twisting of the cords, as the particular and peculiar shape and construction of the rollers 32 and 35 tend to separate the two parts of the 45 cord. The gripping or stop rollers cause instantaneous and positive gripping action on the cord the moment the cord is released by the operator. Of course, instead of providing two 50 separate rollers, 12 and 13 or 26 and 27 or 24 and 25, a single roller with a large and small diameter may be employed. It has been found 55 preferable, however, to make the rollers separate instead of having a single roller of two diameters because the rolling action of each separate roller is permitted to attain its desired rotative speed regardless of the speed attained by the cooperating 60 adjacent roller.

65 The device is relatively simple in construction, is positive and efficient in operation, can be readily and quickly assembled, and it may be applied to existing blinds.

70 Changes may be made in the form, construction and arrangement of the parts, without departing from the spirit of the invention or sacrificing any of its advantages, and the right is hereby reserved to make all such changes as fairly fall within the scope of the following 75 claims.

The invention is hereby claimed as follows:

76 1. In combination, a Venetian blind having a lifting cord of two parts, rollers about which said lifting cord passes, there being a separate roller 75

for each part of the cord, the roller for one part of the cord being greater in diameter than the roller for the other part of the cord, both rollers being mounted on a single axis.

5. 2. In combination, a Venetian blind having a double lifting cord, rollers about which said double lifting cord passes, said rollers being of different diameters and mounted on the same axis.

3. In a Venetian blind, the combination of 10 spaced pairs of rollers, the rollers of each pair being of different diameters being mounted on the same axis, and a double lifting cord operating on said rollers.

4. In a Venetian blind, a pair of rollers mounted on a horizontal axis, a second pair of rollers spaced from said first pair of rollers and mounted on a vertical axis, and other rollers mounted on a horizontal axis and arranged in a plane at right angles to the second named pair of rollers, one 15 roller of each pair being of different diameter than the other roller of the pair.

5. In a Venetian blind, a pair of rollers mounted on a horizontal axis, a second pair of rollers spaced from said first pair of rollers and mounted 20 on a vertical axis, and other rollers mounted on a horizontal axis and arranged in a plane at right angles to the second named pair of rollers, the rollers of each pair being of a different size.

6. In a Venetian blind having a double lifting 25 cord and rollers over which said cord passes, said rollers being of different diameters but mounted on the same axis.

7. In a Venetian blind having a double lifting 30 cord and rollers over which said cord passes, said rollers being of different diameters, and a fixture fastened to a part of said blind and having different size rollers revolutely mounted thereon and over which said cord passes.

8. A Venetian blind fixture comprising a supporting member, a pair of rollers carried by said supporting member and mounted on a vertical axis, a pair of vertical spaced legs carried by said supporting member, a pin passing through said legs, and a pair of rollers revolutely mounted on 40 said pin between said legs, said last named pair of rollers lying in a plane perpendicular to the first named rollers, one roller of each pair having a diameter different from the diameter of the other roller of the pair.

50. 9. In a Venetian blind, means for providing front operation of said blind, comprising a fixture fastened to a part of said blind, said fixture having a supporting ledge, an ear bent from said supporting ledge, a pair of rollers mounted between said ear and a part of said ledge, a pin passing through said ear and a part of said ledge and upon which said rollers are revolutely mounted, a U-shaped bracket extending down-

wardly from said ledge and comprising spaced legs, a horizontal pin passing through said legs, and a pair of rollers mounted on said horizontal pin, a roller of each pair being smaller than the other roller of each pair.

5. 10. In a Venetian blind, a pair of rollers having different diameters, a single axis supporting both of said rollers, and a second pair of rollers having different diameters, a single axis supporting both of said second pair of rollers, said 10 axis of the second pair of rollers being perpendicular to the axis of the first pair of rollers, the smaller roller of said first pair of rollers being substantially the same diameter as the smaller roller of the second pair of rollers and 15 similarly the larger roller of the first pair of rollers being substantially the same diameter as the larger roller of the second pair of rollers.

11. In a Venetian blind, a bracket, said bracket carrying a vertical axis, a pair of rollers, said 20 rollers having different diameters, said rollers being free to move independently of each other on said axis, a second bracket operatively associated with the first bracket, said second bracket carrying a horizontal axis on which is mounted 25 a pair of rollers substantially similar to the first described rollers, said second bracket also carrying a knurled roller mounted therein on an axis substantially parallel to the horizontal axis of the rollers thereon, said roller being slidable toward and away from the horizontal axis of the rollers, and a second knurled roller mounted in the second bracket and rotatable about an axis 30 substantially parallel to the axis of the first knurled roller, said second knurled roller being 35 substantially tangent to a plane parallel to the plane passing between the axis of the first knurled roller and the horizontal axis of the pair of rollers on said second bracket, said plane of tangency cutting through the smallest of the 40 pair of rollers.

12. In a Venetian blind having a double operating cord, and a pair of rollers mounted on an axis and over which said cord passes, the combination of a lock roller mounted on an axis 45 substantially parallel to the axis of the pair of rollers, said lock roller being slidable toward and away from the pair of rollers, and a second lock roller being rotatable about an axis substantially parallel to the axis of the pair of rollers, 50 said second lock roller being fixedly mounted with respect to the pair of rollers and so located in juxtaposition to the pair of rollers and the first lock roller that its surface will be intersected by a line tangent to the first lock roller 55 and the pair of rollers.

GEORGE D. DODGE.
